TIE

Irwin J. DuBon, Garden City, N. Y.

Application May 4, 1932. Serial No. 609,212

1 Claim. (Cl. 2—155)

My invention relates to improvements in neckties, and particularly in neckties of the type which are adapted to be permanently tied and which possess means for enabling the ready removal and installation of the necktie.

It is an important object of my invention to provide a tie structure of this type which is composed of separable sections which are to be joined when the necktie is being made up or for replacing and removing the tie in using and wearing the same.

Other objects and advantages of my invention will be apparent from a reading of the following description of the drawing, wherein:—

15 Figure 1 is a general front elevational view of an embodiment of the invention showing the same made up.

Figure 2 is a plan view of the separable sections.

Figure 3 is an enlarged detailed view of the 20 coupling means showing them connected.

Figure 4 is a perspective view of the end of the wide sections of the tie disclosing the eye coupling member.

Figure 5 is a similar view showing the hook 25 coupling member on the narrow section of the tie.

Referring in detail to the drawing wherein like numerals refer to like parts throughout the same, the numeral 5 refers generally to the wide 30 section of the necktie, and the numeral 6 refers generally to the narrow section of the tie. The invention lies in providing the sections 5 and 6 in suitable lengths with suitable coupling means generally designated 8 placed at a suitable point 35 intermediate the extremities of the tie so that the coupling means will be in a proper position when the tie is made up and worn. The sections are coupled together and then the tie is placed about the neck or other object in the usual manner employed with a non-sectional tie, and the knot 9 formed in the usual way. Then the sections are separated and the tie removed. Replacement of the tie for wearing purposes is easily accomplished by connecting the sections together by 40 means of the coupling generally designated 8. Thus the tie is formed with a perfect knot which lasts the life of the tie, and the tie is not subjected to the usual wear and tear of making up and loosening the knot every time that it is worn.

45 Another advantage is the fact that the construction of the invention enables each individual to form the knot according his own fancy, thereby giving an individualistic touch to the tie of the invention which is not obtainable in ready-tied ties.

The coupling generally designated 8 comprises the eye member 10 connected to the inner end of the large or wide section 5 and the hook member 11 which is similarly attached to the inner end of the narrow section 6. The manner of engaging the hook with the eye 10 is illustrated in Figure 3.

It will be seen that the eye 10 comprises a rectangular formation one longitudinal side of which is rotatably confined by a loop 12 constituted by a portion of the end of the tie section 5 being passed through the eye 10 and then secured by sewing or the like 13 to the opposite side of the tie section end.

The hook member 11 is secured in similar manner to the inner end of the tie section 6 as seen in Figure 5. The hook member comprises a generally rectangular form having the longitudinal straight member 14 from which proceed legs 15 and 16. The legs 15 and 16 are substantially parallel and in the same plane. The legs 15 and 16 are closer together than the ends of the straight portion 14, since bends 17, 18 are provided so as to bring the legs 15 and 16 closer together. This is provided so that the legs may be entered 80 through the eye 10 without requiring that the eye 10 be of a greater longitudinal dimension than the hook member 11. The extremities of the legs 15, 16 have a return bend 19, 20 of the hairpin type so as to constitute a hook formation defined 85 by portions 21 and 22 which extend substantially parallel to the legs 15 and 16, and toward the straight portion 14. The extremities of the portions 21, 22 are joined by a straight member 23 which is substantially parallel to the straight 90 portion 14, but outwardly and laterally removed therefrom so that the same may be easily placed through the eye 10 and the longitudinal side member 24 of the eye may be properly received 95 in the return bends 19, 20 in the manner shown in Figure 3.

It will be obvious that the coupling permits easy assembling and disassembling of the sections of the tie so as to permit installing or removing the tie without disturbing the knot formed therewith, and affording easy means of wearing and removing the tie.

Though I have shown and described herein the preferred embodiment of the invention, it is to be definitely understood that I do not desire to limit 105 the application of the invention thereto, and any change or changes may be made in material and structure and arrangement of parts consistent with the spirit of the invention and the scope of the subjoined claim.

What is claimed is:

In a sectional necktie including a pair of meeting section ends, hook and eye means separably connecting the section ends, said hook and eye
5 eye means comprising an elongated eye through which one of the section ends is passed and then secured to the side of the section end so as to secure one longitudinal side of the eye to the section end, and a closed loop forming a hook of
10 the same longitudinal dimension as the eye and through which the remaining section end is passed and then secured to one side of the remaining section end so as to secure one longitudinal side

of the hook to the remaining section end, a portion between the ends of the opposite sides of the hook being displaced outwardly and then laterally and return bent to provide a hook form for passing through the said eye and engaging the free longitudinal side of the eye, the hook form being of a size to engage the ends of the eye when so engaged with the free longitudinal side of the eye whereby movement of the hook relative to the eye in a direction transversely of the section ends is prevented. 80 85
